(57) **CLAIM**

The ornamental design for an illumination assembly for an imaging system, as shown and described.

DESCRIPTION

The sole FIGURE is a front elevation view of an illumination assembly for an imaging system.

The ornamental design that is claimed is shown in solid lines in the drawings. The broken lines in the drawings show portions of the illumination assembly that form no part of the claimed design. In particular, the dash-dot-dash broken lines show the bounds of the claimed design and form no part of the claimed design.
